(57) **CLAIM**

The ornamental design for a dentifrice, as shown and described.

DESCRIPTION

The dentifrice is at least partially transparent with suspended hexagonal shaped pieces.

FIG. 1 is a perspective view of a segment of the dentifrice of my design;

FIG. 2 is a side elevation view thereof.

FIG. 3 is an end elevation view thereof; and,

FIG. 4 is a top plan view thereof.

The broken line showing of a toothbrush and tube are for illustrative purposes only and form no part of the claimed design.
